UNITED STATES PATENT OFFICE.

ERNEST ALSCHULER, OF NEW YORK, N. Y.

BATTERY HAND LAMP.

Application filed June 21, 1920. Serial No. 390,509.

To all whom it may concern:

Be it known that I, ERNEST ALSCHULER, a citizen of the United States, and residing at New York, New York, have invented the 5 new and useful Improvement in Battery Hand Lamps, of which the following is a specification.

This invention relates to battery hand lamps such as may be lighted by the 10 usual operation of the switch on the casing, while the lamp is held in the hand.

In many types of construction such a lamp is provided with a casing of insulating material provided with metal fittings which 15 may be included in the lamp circuit. Such lamps are also usually provided with a switch on the casing which may be closed by the operation of a push button or other moving part on the exterior thereof. Such 20 lamps are subject to the disadvantage that when they are carried in a tool box or similar receptacle along with a number of other articles, the lamp circuit is liable to be closed accidentally either by operation of the 25 switch or by establishing metallic contact between the various fittings and consequently the battery is liable to be exhausted unnecessarily.

One of the objects of this invention, therefore, 30 is to provide a lamp construction which will insure against the accidental discharge of the battery.

In such constructions it is usually necessary to insulate some of the metallic fittings, 35 and for this purpose the fitting on the upper or reflector end may be insulated.

Another object of this invention, therefore, 40 is to provide novel means for insulating the lamp circuit, particularly at the reflector end of the casing.

Another object is to provide a lamp construction which is simple and cheap to manufacture and reliable in operation.

Further objects will appear from the detailed description taken in connection with the accompanying drawings, in which:

Figure 1 is a sectional view of a hand lamp embodying this invention;

Figure 2 is an enlarged sectional detail 50 of the insulating support for the reflector;

Figure 3 is an enlarged sectional detail of the end cap construction; and,

Figure 4 is a sectional view of the lower 55 end of the lamp showing the end cap partly unscrewed, so as to break the lamp circuit.

Referring now to the accompanying

drawing, 1 designates the casing, which in this case is shown as of insulating material containing a battery 2, one of whose terminals connects with one terminal of the lamp 60 3 mounted in the reflector 4 in the usual manner. The upper end of the reflector 4 bears against the lens 5, which is clamped to the casing part or housing 6 by means of the ring 7. The housing 6 is bent inwardly to form an internal annular shoulder as shown at 8. On this shoulder is mounted a metal ring 9 into which is fitted an insulating ring 10. The insulating ring 10 is adapted to engage the reflector 4 at an intermediate portion thereof so as to support it and center it in the casing. The upper end of the reflector 4, where it bears against the lens 5 is of less diameter than the ring 7, so as to be separated therefrom for insulating purposes. The housing 6 is screwed on to the sleeve 11 on the upper end of the casing in the usual manner.

A switch 12 which may be such as has been described and illustrated in Patent No. 1287262, December 10, 1918, is mounted on the casing. A conductor 13 connects the switch 12 with the reflector 4. This conductor passes upwardly on the inside of the casing, to which it may be attached by a rivet 85 14 at the upper end, and extends beyond the upper end of the casing 1 a sufficient distance so that when the housing 6 is screwed in place on the sleeve 11, the conductor 13 will pass up inside of the insulating ring 10 90 to make contact with the reflector 4. The head of the rivet 14 may be counter sunk in the casing 1, so as to avoid contact with the sleeve 11.

It will be seen that as the housing 6 is 95 screwed down upon the sleeve 11 the conductor 13 will be forced upwardly between the reflector 4 and the insulating ring 10 and will, therefore, be sustained in good contact with the reflector by the ring 10. It 100 will also be seen that the outside metallic fittings 6, 7 and 11 are entirely insulated from the circuit.

From the switch 12 a conductor 15 passes 105 downwardly to the end of the casing where it is turned over, so as to contact with, and being held by the flange 16 on the lower screw sleeve or fitting 17.

The usual metallic end cap 18 may be provided to be screwed on to the sleeve 17. 110 Within the cap 18, but insulated therefrom by means of the flanged insulating washer

19, is a metallic disc, having an overturned flange 21 adapted to receive and retain one coil of the usual battery supporting spring 22. These parts are so arranged that when 5 the cap 18 is screwed up on the sleeve 17, the flange 21 will contact with the flange 16, thereby completing the circuit from the battery to the switch 12.

It will be seen that since the lamp circuit 10 is completed through the contact between the flanges 16 and 21, said circuit may be opened by unscrewing the cap 18, so as to separate those flanges. It will also be seen that with 15 these flanges so separated, it will be impossible to light the lamp by manipulation of the switch 12 or by any accidental contact which may establish an external circuit between any of the outside metal fittings.

It is further evident that the reflector 4, 20 being clamped between the lens 5 and the ring 10, is completely supported in the housing 6, and that when said housing is unscrewed from the sleeve 11 the circuit between the reflector and the strip 13 will be 25 broken, thereby rendering it impossible to light the lamp by manipulation of the switch 12, or by establishing a circuit between the end fittings.

It will be seen, therefore, that this invention 30 accomplishes its objects in providing a lamp structure wherein the external metal fittings may be so insulated as to make it impossible to close the battery circuit by establishing metallic contact therebetween. 35 It will also be noted that this is accomplished by providing novel means for insulating and supporting the reflector in the casing and by novel means of establishing a circuit therewith all insulated from the external fittings. 40 It will further be noted that by means of the circuit opening device, in the end cap, the establishment of any accidental circuit which may exhaust the battery is rendered impossible.

45 It is obvious that various changes may be made in the details of construction, within the scope of the appended claims, without departing from the spirit of this invention; it is, therefore, to be understood that this 50 invention is not to be limited to the specific details shown and described.

Having thus described this invention, what is claimed is:

1. In a battery hand lamp having a battery 55 receiving casing provided with a movable cap, a lamp in the casing, a spring in the casing adapted to support and contact with the battery, and a circuit-closing switch on the casing adapted to normally connect 60 the lamp with the battery through the spring, a fixed conductor extending along the casing and connected with the switch and a spring retainer mounted in but insulated from the cap and having a circumferential flange taking over and retaining said spring and mak-

ing connection with said switch through said conductor.

2. In a battery hand lamp having a battery receiving casing provided with a movable cap, a lamp in the casing, a spring in 70 the casing adapted to support and contact with the battery, and a circuit-closing switch on the casing adapted to normally connect the lamp with the battery through the spring, a metal rim on the casing and connected with the switch, and a spring retainer mounted in but insulated from the cap and having a circumferential flange taking over and retaining said spring and contacting with said rim. 75

3. In a battery hand lamp having a battery receiving casing provided with a metal part, a metal reflector in the lamp circuit and a lens against which the reflector bears, a metal support secured to said casing part and 85 an insulating member seated in said support and providing a seat for the reflector between its rim and its nipple. 80

4. In a battery hand lamp having a battery receiving casing provided with a metal part, a metal reflector in the lamp circuit and a lens against which the reflector bears, a metal support secured to said casing part, 90 an insulating member seated in said support and providing a seat for the reflector between its rim and its nipple, and a conductor within said insulating member adapted to contact with the reflector. 95

5. In a battery hand lamp having a battery receiving casing provided with a metal part, a lamp in the casing, a reflector in the lamp circuit, a movable cap on the casing, a spring adapted to support and contact with the battery, and a circuit-closing switch adapted to normally connect the lamp with 100 the battery through the reflector and the spring, a metal support on the casing part, an insulating member on the support in which the reflector is adapted to seat, and a spring retainer having a rim adapted to receive and retain a coil of the spring mounted in but insulated from the cap, said rim being adapted to form a contact for connection with the switch. 105

6. A battery hand lamp, comprising, a battery receiving casing provided with an exterior end fitting in the lamp circuit, an end cap mounted on said fitting, and an element mounted in but insulated from said cap connected with the battery and adapted to contact with said fitting. 115

7. A battery hand lamp, comprising, a battery receiving casing provided with an exterior end fitting in the lamp circuit, an end cap mounted on said fitting, an element mounted in but insulated from said cap, and a spring carried by said element and engaging the battery, said element being adapted to contact with said fitting. 125

8. A battery hand lamp, comprising, a 130

battery receiving casing provided with an exterior end fitting in the lamp circuit, an end cap mounted on said fitting, an element mounted in but insulated from said cap and 5 connected with the battery, and a flange on said fitting adapted to contact with said element.

9. A battery hand lamp, comprising, a battery receiving casing provided with an 10 exterior end fitting in the lamp circuit, an end cap mounted on said fitting, an element mounted in but insulated from said cap, a spring carried by said element and engaging the battery, and a flange on said fitting 15 adapted to contact with said element.

10. In a battery hand lamp having a battery-receiving casing provided with a movable cap, a lamp in the casing, a spring in the casing adapted to support and contact with the battery, and a circuit-closing switch 20 on the casing adapted to normally connect the lamp with the battery through the spring, a metal rim on the exterior of the casing and connected with the switch, means in said cap adapted to connect said rim with said spring, 25 and means adapted upon moving said cap to disconnect said rim.

In testimony whereof I affix my signature this 31st day of March, 1920.

ERNEST ALSCHULER.
